UNITED STATES PATENT OFFICE.

ARTHUR M. BURNHAM, OF GARDINER, MAINE, ASSIGNOR TO ALBERT M. SPEAR, OF SAME PLACE.

MOP-WRINGER.

SPECIFICATION forming part of Letters Patent No. 619,664, dated February 14, 1899.

Application filed August 30, 1898. Serial No. 689,855. (No model.)

To all whom it may concern:

Be it known that I, ARTHUR M. BURNHAM, a resident of Gardiner, in the county of Kennebec and State of Maine, have invented certain new and useful Improvements in Mop-Wringers; and I do hereby declare the following to be a full, clear, and exact description of the invention, such as will enable others skilled in the art to which it appertains to make and use the same.

My invention relates to an improvement in mop-wringers, the object of the invention being to provide a mop-wringer which shall be simple in construction, which can be conveniently and easily packed into a small space for shipment, which will be comparatively cheap to manufacture, and which will be strong and durable when in use.

With these objects in view the invention consists in certain novel features of construction and combinations and arrangements of parts, as will be more fully hereinafter described, and pointed out in the claims.

In the accompanying drawings, Figure 1 is a side view of my improved wringer. Fig. 2 is a sectional view. Fig. 3 is a plan view; and Fig. 4 is a horizontal section, with the bucket shown in dotted lines. Fig. 5 is a side elevation opposite to that shown in Fig. 1. Fig. 6 is a detail view of the fixed roller, its mountings, and the guides e. Fig. 7 a detail view of the movable roller and its mountings.

A represents a pail or bucket, and B my improved wringer. A piece of metal a (preferably steel or bond-iron) is bent between its ends to form the rear base portion of the frame, and the respective ends are preferably bent slightly toward each other, as shown at 1 1, and then made to project forwardly parallel with each other a sufficient distance, as shown at 2 2, to form an extended bearing for the base and preclude any possibility of the bucket or pail tipping forward when the operator's foot is placed on the treadle. A cross-piece b is bent at its ends 3 3 to form bearings against the side pieces 2 2 and is provided with holes in the ends 3 3, in alignment with holes in the pieces 2 2 to receive rivets or bolts 4 4, to secure said parts together. Arms 24 24 are secured to the pieces 2 2 and provided with rearwardly-projecting

teeth 25 25, adapted to engage the bucket and prevent any forward, sidewise, or vertical movement thereof. An arm or lug 26 is pivotally attached to the rear base portion 55 and provided with a screw-threaded hole at its upper end to receive a thumb-screw 28, provided with a conical end 29 to engage the bucket and prevent any rearward or vertical movement thereof. The bucket or pail is preferably provided with a metal plate 30 with a hole or holes 31 therein to receive the conical end of the screw 28. It will be seen that this plate 30 will prevent wear on the bucket due to the forcing forward of the thumb-screw. 65 The arm or lug 26 is pivotally attached to said base, so that it can be swung to one side when it is desired to remove the bucket or pail.

Parallel uprights c c, provided with rearwardly-extending arms 55 at their lower ends, are secured to the base portion by means of bolts 6 6, passing through holes in said arms 5 and the base. The upper ends of said uprights are made approximately the shape 70 of an inverted U (or hook-shaped) and provided with inwardly-projecting lugs 7 7, to which a cross-piece 8 is secured by means of bolts 9 or other approved means. A roller d is revolvably mounted in the bent upper ends 80 of the uprights c, said roller preferably made of wood and provided at its ends with metal plates or disks 10 10, whereby to prevent wear on the roller. The ends of the roller are made convex in order to prevent parts of 85 the mop becoming entangled about the journals of the roller. Guides e e are pivoted to the lugs 7 7 so they can be swung toward each other and partly under the roller to permit the insertion or withdrawal of the pail, and 90 said guides are adapted to guide the mop between the rollers and prevent the mop becoming wound around or tangled on one of the rollers.

Upwardly-extending arms or lugs f f are 95 secured to the portion 1 of the base by means of bolts or rivets 11. The movable roller g is mounted in a frame 12, which is composed of a single piece of metal having its cross-bar bent between its ends to form a depression 100 13, in which the roller g is mounted. This roller is preferably provided with convex ends

for the purpose heretofore described in connection with the stationary roller.

The depending or upright portions 16 16 of the frame 12 are pivotally connected at 5 their lower ends by means of bolts 17 17 to the portions 1 of the base. Arms 18 18, secured to the uprights 16 of the frame 12, are pivoted on said bolts 17 and provided at their outer ends with inwardly-projecting lugs or 10 shoulders 19 19. Links 20 20 connect the uprights 16 16 and arms 18 18. A foot-lever *h*, composed, preferably, of a single piece of 15 spring metal and bent around the frame, is pivotally connected at its ends to the upper ends of lugs or arms *ff* by means of bolts 21 21 and nuts 22 22, the pivoted supports of the foot-lever being thus disposed immediately over the pivotal support of the swinging frame to the base. The foot-lever is adapted to normally 20 rest on the lugs or shoulders 19 19, whereby when the foot-lever is forced downward it will force forward the movable roller *g*. A treadle 23 of any approved construction 25 is secured to the foot-lever, preferably centrally between its ends. A spring *i*, preferably of wire, is secured to one of the bolts 17 at one end and bent at its other end to bear against one of said uprights 16, whereby to normally hold the movable roller away from 30 the stationary roller, and when the movable roller is pushed forward and the foot-lever released the spring *i* will serve to throw the movable roller back to its normal position.

As before stated, the frame is made of steel, 35 and it will be observed that the parts of the frame are so disposed and the movable parts so constructed thereto that the strain will come edgewise on the material.

By making the foot-lever of spring metal 40 sufficient elasticity will be afforded to permit the mop to be drawn between the rollers when said mop gets uneven or knotty, without endangering the several parts of the wringer.

Various slight changes might be made in 45 the general form and arrangement of the several parts described without departing from the spirit and scope thereof, and hence I would have it understood that I do not wish to limit myself to the precise construction set 50 forth, but consider myself at liberty to make such slight changes and alterations as fairly fall within the spirit and scope of my invention.

Having fully described my invention, what 55 I claim as new, and desire to secure by Letters Patent, is—

1. In a mop-wringer, the combination with a base, of a stationary roller-frame secured to said base, a roller in said frame, lugs on 60 said base, a movable roller-frame pivotally connected to said base, a roller in said last-mentioned frame, arms pivotally connected with said base, links connecting said arms and movable roller-frame, and a foot-lever 65 pivotally connected to said lugs and adapted

to bear against said arms and move the movable roller-frame.

2. In a mop-wringer, the combination with a base, fixed standards secured thereto and a roller mounted in said fixed standards, of a 70 roller-frame pivotally attached to said base and carrying a roller, an arm fixed to said pivoted frame and a foot-lever pivotally supported by the frame and adapted to engage said fixed arm whereby to swing the pivoted 75 frame and move the roller therein toward the fixed roller.

3. In a mop-wringer, the combination with a base, fixed standards secured thereto and a roller mounted in said fixed standards, of a 80 roller-frame pivotally attached to said base and carrying a roller, an arm fixed to said pivoted frame, lugs secured to said base at the pivotal point of the movable frame, and a foot-lever pivoted to the said lugs at a point 85 above the pivotal point of said movable frame and adapted to bear against the rigid arm secured to the movable frame.

4. In a mop-wringer, the combination with a base, fixed standards secured thereto and a 90 roller mounted in said fixed standards, of a roller-frame pivotally attached to said base and carrying a roller, an arm fixed to said pivoted frame, lugs secured to said base at the pivotal point of the movable frame, a 95 foot-lever pivoted to the said lugs and coöperating with the fixed arm on the movable frame to force the movable roller toward the stationary roller and a spring adapted to force the movable roller back to its normal position. 100

5. In a mop-wringer, the combination with a base, fixed standards secured thereto and a roller mounted in said fixed standards, of a 105 roller-frame pivotally attached to said base and carrying a roller, an arm fixed to said pivoted frame and provided with an inwardly-extending shoulder and a lever pivoted to said frame and adapted to bear against the shoulder on the arm and operate the movable roller and a spring on said frame to force the movable roller back to its normal position. 110

6. In a mop-wringer, the combination with a base, and a roller mounted in rigid bearings, of a pivoted frame, a roller mounted in said pivoted frame, arms pivotally connected with 115 the base, connections between said arms and the pivoted frame, and a foot-lever having yielding arms, said yielding arms pivotally connected with the base in proximity to the pivotal connection of said pivoted arms thereto and bearing at points between their ends on said pivoted arms, substantially as set forth.

In testimony whereof I have signed this specification in the presence of two subscribing 125 witnesses.

ARTHUR M. BURNHAM.
